W. A. SMITH

ROCK DRILL OILING DEVICE

Filed June 20, 1925

INVENTOR.
William A. Smith
BY *Nicholas G. Ogden*
HIS ATTORNEYS.

UNITED STATES PATENT OFFICE.

WILLIAM A. SMITH, OF ATHENS, PENNSYLVANIA, ASSIGNOR TO INGERSOLL-RAND COMPANY, OF JERSEY CITY, NEW JERSEY, A CORPORATION OF NEW JERSEY.

ROCK-DRILL-OILING DEVICE.

Application filed June 20, 1925. Serial No. 38,475.

This invention relates to fluid actuated rock drills, but more particularly to an oiling device for rock drills of the hammer type.

- 5 Usually rock drills of the hammer type are equipped with means for automatically lubricating the working parts of the machine. Various means have been devised for accomplishing this purpose such as for 10 instance the pulsation of pressure fluid into and out of the reservoir whereby minute quantities of oil are carried into the internal working parts of the machine at each stroke of the piston. In this type of oiler, the 15 passages leading through the reservoir are necessarily of small cross sectional area and in consequence are liable to become clogged by dirt or other foreign matter.

It is accordingly an object of this invention 20 to prevent clogging of the oil passage leading from the oil reservoir.

Another object is to introduce oil to the working parts of the machine immediately after each period of operation.

- 25 A further object is to connect the oil reservoir with the pressure fluid supply for admitting pressure fluid into the reservoir while the drill is in operation and to enable the oil to be carried to the working parts 30 of the machine by the expansion of the pressure fluid in the reservoir after the piston stops reciprocating.

Other objects will be in part obvious and in part pointed out hereinafter.

- 35 The invention consists of the combination of elements, features of construction and arrangement of parts having the general mode of operation substantially as hereinafter described and more particularly pointed out in 40 the appended claims and illustrated in the accompanying drawings, in which—

Figure 1 is a longitudinal view in section of a rock drill in which is embodied one form which the invention may assume in 45 practice, and

Figure 2 is a perspective view of a front cylinder washer constructed in accordance with the practice of the invention.

- 50 Referring to the drawing, the invention is shown embodied in a rock drill in which a cylinder A and a back head B are secured to each other by means of the usual side bolts (not shown). A hammer piston C is arranged to reciprocate within the cylinder 55 and in this instance is provided with a

smooth unbroken forward extension D for delivering blows upon a drill steel E supported within the forward end of the cylinder A. A back cylinder washer F forms a closure for the rearward end of the cylinder A. A front cylinder washer G which is preferably pressfitted into the front end of the cylinder is provided with a bore H to receive the piston extension D and to cooperate with said extension for sealing the front end of the cylinder. A valve chest which in this instance comprises a main body portion J, a spacer K and a bottom plate L is secured to the side of the cylinder A by means of bolts O and is provided with a chamber P to receive a distributing valve Q adapted to oscillate about a pin R.

Pressure fluid is supplied to the valve chest through a connection S held in position by a screw threaded plug T. The admission of pressure fluid to the machine is controlled by a throttle valve U which communicates with the valve chamber P through a supply passage V. The admission of pressure fluid to the front and rear ends of the cylinder A is effected through admission ports W and X respectively and the pressure fluid is exhausted from the cylinder through an exhaust port Y which communicates with the atmosphere through a passage Z formed between the cylinder A and the bottom plate L.

In accordance with the practice of the invention, the front cylinder washer G is provided with an external annular chamber b 99 to form an oil reservoir whereby oil may be supplied to the working parts of the machine. A pair of small annular external grooves c are formed near the ends of the washer G and communicate with the reservoir through passages d and also communicate with the supply passage V through a passage e and ports f. The oil is introduced into the reservoir b through an opening g which is normally sealed by a suitable filler 95 plug h.

In the operation of the device, whenever the throttle valve U is opened to admit pressure fluid to the valve chamber P, a portion of the pressure fluid will pass through the passage e, the ports f into the grooves c and thence through the passages d into the reservoir b. The pressure fluid thus entering the reservoir b will tend to prevent the oil from flowing into the passage e, but after each pe- 110

- riod of operation when the throttle valve *U* is closed, the pressure fluid confined within the reservoir *b* will tend to expand and force the oil from the reservoir *b* into the grooves *c* through the passages *d* and thence through the ports *f* and through the passage *e* into the valve chest *P*. In this way, a predetermined amount of oil is supplied for the succeeding period of operation.
- 10 This method of lubricating rock drills has been found to be very efficient in operation. Its advantages reside in the fact that it is economical, and that owing to the comparatively large cross sectional area of the passage leading from the reservoir, the danger of clogging of said passage is eliminated. Another desirable advantage is that this construction permits of close regulation of the oil supply with respect to the period of 15 operation, depending of course to some extent, upon the nature of the rock being drilled. This, however, may readily be determined by the operator after a little practice and the operator may at all times know 20 approximately the amount of oil within the reservoir since the consumption of the oil is directly proportional to the number of times the drill is set in operation, since approximately an equal amount of oil is carried 25 from the reservoir after each period of operation. In this way, the possibility of the machine running dry is eliminated.

I claim:

1. In an oiling device for rock drills, the combination of a cylinder, a reciprocatory hammer piston in the cylinder, a valve chest having a valve chamber and a main supply passage, a throttle valve in said chest, a front cylinder washer within the cylinder 35 provided with an external annular chamber forming an oil reservoir, external annular grooves in the washer in communication with the annular chamber, a passage leading from the annular grooves to the main supply passage to admit pressure fluid from the supply passage into the reservoir while the drill is in operation and to permit the

conveyance of oil by expanding pressure fluid from the reservoir into the valve chamber immediately after the throttle valve is closed.

2. In an oiling device for rock drills, the combination of a cylinder, a reciprocatory hammer piston in the cylinder, a valve chest having a valve chamber and a main supply passage, a throttle valve in the chest, a front cylinder washer provided with an external annular chamber forming an oil reservoir, external annular grooves on the washer, passages providing communication between the annular chamber and the annular grooves, and a passage leading from the annular grooves to the supply passage to admit pressure fluid into the annular chamber during the operation of the drill to prevent oil from flowing from the annular chamber and to convey oil from said annular chamber to the valve chest after the drill ceases to operate.

3. In an oiling device for rock drills, the combination of a cylinder, a reciprocatory hammer piston in the cylinder, a valve chest having a valve chamber and a main supply passage, a distributing valve in the valve chamber, a throttle valve in the chest to control the supply passage, a front cylinder washer in the cylinder having an external annular chamber forming an oil reservoir, external annular grooves near the ends of the front cylinder washer, passages providing communication between the annular chamber and the annular grooves, and a passage communicating at one end with the annular grooves and at its other end with the supply passage at a point between the throttle valve and the valve chamber for conveying pressure fluid into the annular chamber during the operation of the drill and for conveying oil from the annular chamber into the valve chest immediately after the throttle valve is closed.

In testimony whereof I have signed this specification.

WILLIAM A. SMITH.
